UNITED STATES PATENT OFFICE.

PETER EYERMANN, OF WITKOWITZ, AUSTRIA-HUNGARY.

ELECTRIC FURNACE.

1,189,356.

Specification of Letters Patent.

Patented July 4, 1916.

Application filed December 5, 1912. Serial No. 735,091.

To all whom it may concern:

Be it known that I, PETER EYERMANN, a citizen of the United States, residing at Witkowitz, Moravia, in the Empire of Austria-Hungary, have invented a new and useful Improvement in Electrical Furnaces, of which the following is a specification.

This invention relates to electrical furnaces and more particularly to furnaces of this kind for operating on metals, ores or the like.

The objects of the invention are to produce an efficient and reliable electric furnace which can be built in large sizes without complicating the construction or reducing the efficiency of operation thereof; also to so mount the crucible of the furnace that it can readily be tilted to completely empty the same; also to improve the construction of furnaces of this kind in the respects hereinafter mentioned.

The accompanying drawing shows a sectional elevation of a furnace embodying the invention.

Briefly stated, the furnace comprises a crucible which is mounted in a supporting frame or cradle and a roof or arch for the crucible supported over the same and through which the electrodes pass, the crucible and roof being so arranged that one is rotatable relative to the other to permit the current from the electrodes to act on different portions of the crucible during the operation of the furnace. In the construction shown the crucible is rotatable relatively to the supporting frame or cradle, and the frame adapted to be tilted to pour the charge out of the crucible.

In the particular embodiment of the invention shown in the drawings, 1 represents a vessel, crucible, or container for the material to be acted upon and which may be constructed in any usual or suitable manner, for example, the crucible may comprise an outer metal housing containing the usual acid or basic lining of refractory material.

The crucible is suitably mounted on a supporting frame in such a manner as to permit the crucible to be rotated relatively to the frame. The crucible shown is supported on a frame or cradle 5 by means of annular bearings 2, ball bearings being employed in the construction shown, and an upright pivotal bearing 24 at the axis of rotation of the crucible, which holds the crucible at all times central with regard to the frame 5. Suit-

able guide members 4 on the crucible and the frame also serve to prevent the displacement of the crucible relatively to the frame. Rotary motion may be imparted to the crucible in any desired manner, for example, by means of a worm 10 engaging with a suitable gear attached to the crucible. The worm is driven through intermediate gearing by means of an electric motor 11 or other source of power.

The frame 5 is mounted on a suitable base 27 in such a manner that the metal or slag contained therein can be poured off by tilting or rocking the frame. For this purpose the base or lower portion of the frame in the construction shown is made curved or in the form of a rocker and is adapted to be rocked on the base 27 by hydraulic or other power operated mechanism, as shown at 23.

The crucible is covered by an arch or roof 6 of refractory material which is suitably secured in a reinforcing member or truss 15 supported at 7 on the frame 5 of the crucible.

The roof is provided with holes or openings through which electrodes 8 extend. The electrodes may vary in number, and are so arranged on the roof that the center line 35 of the group of electrodes, represented by the line 19-19, will be eccentric with regard to the axis of rotation of the crucible, represented by the line 3-3, so that when the crucible is rotated on its axis each of the 90 electrodes describes a different path relatively to the charge in the crucible, thus subjecting the various parts of the metal bath to the action of the current. The electrodes may dip into the metal, indicated at 9, or 95 into the slag 9^a, or may be held at the surface of the bath, as indicated at 22. Other electrodes 8^b may be arranged in the walls of the crucible and current is conducted to these electrodes by means of brushes or the 100 like 30 engaging a contact ring 31 which is secured on and insulated from the frame 5.

A clearance space 26 between the crucible and the roof may be packed in any suitable manner to make a tight joint and to permit 105 relative motion between the roof and the crucible.

21 represents guides or collars for the electrodes at the roof of the crucible.

The electrodes may be held in operative 110 relation to the bath and are adjustable relatively to the bath in any suitable manner.

In the construction shown the electrodes are suspended from an arm or crane 16 which is mounted on a base 18 at one side of the furnace and which extends over the 5 crucible. The crane is preferably constructed to turn about the axis of a pivot or trunnion 17 so that the electrodes can be swung to a position at one side of the furnace when it is desired to change the electrodes or to 10 repair the furnace.

25 represents an attending floor from which the furnace can be charged through charging doors or openings, such as indicated at 20, and from which the action of 15 the furnace can be observed.

For pouring a discharging material from the furnace, a tapping spout 12 is provided on the crucible. This spout may be rigidly secured to the crucible or may be made readily detachable so that it can be placed in operative relation only when it is desired to pour off metal or slag, and can be removed from the furnace during the rotation of the crucible, suitable attaching means or flanges 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450

Electric furnaces of the kind described require only a small number of electrodes owing to the relative movement between the electrodes and the crucible, so that each electrode acts on a considerable portion of the bath, thus insuring a uniform treatment of the same. The relative rotation of the crucible with regard to the electrodes keeps the metal bath more or less agitated and this also helps to maintain a more uniform treatment throughout the bath. When furnaces of this kind are built in larger sizes, the electrical connections do not become complicated as they do in furnaces in which a large number of electrodes are used, and the losses of power incident to the employment of a large number of electrodes are eliminated. The furnace described also has the advantage that it can be readily tilted in such a manner that all the metal contained therein can be poured off. This adds greatly to the efficiency of the furnace and avoids the treating for the second time of a portion of the previous bath.

I claim as my invention:

1. In an electric furnace, the combination
60 of a crucible, electrodes extending into the
crucible, means for producing relative ro-
tary movement between the crucible and said

electrodes, and means for tilting the crucible for pouring the charge out of the same.

2. In an electric furnace, the combination 65
of a crucible, electrodes extending into said
crucible, means for producing a relative ro-
tary movement between the crucible and
the electrodes, a supporting frame in which
said crucible is held, and means for tilting 70
the frame for pouring the charge out of the
same.

3. In an electric furnace, the combination of a crucible, a frame supporting said crucible, a roof for the crucible supported on said frame, electrodes extending through said roof into said crucible, means for producing relative rotary movement between the crucible and said roof, and means for tilting said supporting frame. 80

4. In an electric furnace, the combination of a crucible, a roof for the crucible, actuating means for producing relative movement between said crucible and said roof, electrodes extending through said roof and held against movement relatively thereto, and a frame supporting said crucible, said roof and said actuating means. 85

5. In an electric furnace, the combination of a crucible, a roof for the crucible, electrodes extending through said roof, actuating means for producing relative movement between said crucible and said roof, a movable frame supporting said crucible, said roof and said actuating mechanism, and means for moving said frame for pouring material out of said crucible.

6. In an electric furnace, the combination of a frame, bearings mounted on said frame, a crucible supported on said bearings and 100 rotatable relatively to said frame, means on said frame for holding the crucible in place, and means for tilting said frame.

7. In an electric furnace, the combination of a crucible, means for rotating said crucible, electrodes extending into the crucible and arranged eccentrically with regard to the axis of rotation thereof, and means for tilting said crucible. 105

8. In an electric furnace, the combination 110
of a crucible, means for rotating said cruci-
ble, electrodes extending into the crucible
and arranged eccentrically with regard to
the axis of rotation thereof, electrodes ar-
ranged in the walls of said crucible, and 115
means for tilting the crucible.

In testimony whereof I have signed my name to this specification in the presence of two witnesses.
